UNITED STATES PATENT OFFICE.

LOUIS A. ANDREWS, OF NEWTON UPPER FALLS, MASSACHUSETTS.

TIRE-PUMP.

1,178,122.

Specification of Letters Patent.

Patented Apr. 4, 1916.

Application filed October 26, 1914. Serial No. 868,605.

To all whom it may concern:

Be it known that I, LOUIS A. ANDREWS, a subject of the King of Italy, and a resident of Newton Upper Falls, in the county of 5 Middlesex and Commonwealth of Massachusetts, have invented certain new and useful Improvements in Tire-Pumps, of which the following is a full, clear, and exact specification.

10 This invention relates to that type of air pumps especially designed for inflating pneumatic tires, wherein the piston is provided with a cupped disk of leather adapted by the engagement of its flanged edges 15 against the interior of the pump-cylinder to make the piston air-tight during its down stroke. The chief difficulty with this is that after a time the cupped edges of the leather become permanently flexed inward and so 20 fail to contact with the interior of the cylinder, consequently failing to be air-tight and rendering the pump useless.

The purpose of this invention is primarily the effecting of means for preventing above 25 recited inward flexing of the leather washer. To accomplish this, I provide at the end of the cylinder an expander adapted temporarily to press outward the cupped edges of the leather washer, and so to insure their 30 contact with the cylinder.

Referring to the drawings forming part 35 of this specification, Figure 1 is a side sectional view, substantially full size, of a hand pump embodying the primary feature of my improvements. Fig. 2 is a similar section, but on a smaller scale, of a double-acting pump made in accordance with my invention. Fig. 3 is a similar section of a two-cylinder pump embodying my improvements. Fig. 4 is a detail sectional view of 40 the double acting valve used in connection with the double acting pump shown in Fig. 2. Fig. 5 is a sectional detail view of the ball valve used in the construction disclosed 45 in Fig. 3.

In the simplest form of the invention shown in Fig. 1, the cylinder 1 is expanded at its lower end to compose an annular recess 2 of larger diameter than the cylinder, 50 in order to provide a space into which the cupped edges 3 of the washer 4 can be forced by the expander. Centrally within the cylinder end is located the expander, which preferably consists of a conical ring 55 5 the smaller diameter of which is less than that which can ever be taken by the cupped

edges 3, while its largest diameter is in excess of that of the interior of the cylinder 1. Consequently, when the piston is pressed down to the lower end of the cylinder, the 60 cupped edge of the washer 4 is entered by said ring and pressed diametrically outward into the annular space 2 and given a larger diameter than the interior of the cylinder. When, now, the piston is withdrawn, the 65 cupped edge rides up the curved shoulder 6 and is contracted to the diameter of the cylinder, but with a slight resilient outward pressure which causes it to fit the cylinder perfectly. I prefer to have the ring 5 high 70 enough to meet the metal washer 7 of the piston before the cupped edge 3 can reach the bottom of the recess 2, in order to preserve said edge against injury. It is also quite essential to provide the said recess, as 75 otherwise there would have to be a comparatively sharp V-groove to receive the cupped edge, which would not only injure said edge, but would not insure its air-tight fit against the cylinder; for, as is well known in the 80 construction of metal springs, a body which is not absolutely inelastic must be bent beyond the desired point in order to remain thereat. Hence the necessity of pressing the cupped edge to a larger diameter than 85 that required.

In Fig. 2 is illustrated a double action pump having the cupped washers 4 facing in opposite directions, and provided with the expander rings 5 and annular recesses 90 2 at both ends. The heads 9 are joined by a pipe 10 connected by conduits 11 with the interior of the cylinder 12, and from this pipe runs the usual rubber tube 13 by which the compressed air is delivered to the 95 pneumatic tire. At the juncture of the pipe 10 and the nipple 14 to which the rubber tube is attached, is a chamber 15 containing a ball 16, and both above and below said juncture is a valve seat 17, so 100 that when the air is compressed in one section of the cylinder, said ball is forced into contact with the seat 17 which closes the air from entering the other section, and so causes the air to be delivered through the 105 rubber tube 13. (See Fig. 4.)

In the double cylinder pump illustrated in Fig. 3, the cylinder 12 is formed with the expander ring 5 and annular recess 2 at its lower end alone, and the cupped washer 4 110 opens downward. Beside this cylinder is a second one 19 of substantially the same

length but of considerably less diameter. In this secondary cylinder 19, the expander ring 5 and recess 2 are at the upper end thereof, and the washer 4 is cupped upward. A conduit 20 opens from the main cylinder 12 to the secondary cylinder 19, and the compressed air is taken from the top end of the cylinder 19 through a conduit 21 and rubber tube 13.

- 10 As shown in Fig. 5, the lower end of the piston rod 22 is tubular and provided with a ball valve 23 and seat 24, and above the piston is a radial hole 25 opening out into the cylinder 19, in order that the air may 15 pass from beneath to above the piston as the latter descends, but none such can pass as the piston rises.

The operation of this double pump is as follows: When the handle 26 is pushed 20 downward, the air in the cylinder 12 beneath the piston therein is forced out therefrom into the cylinder 19, passing through the tubular lower end of the piston rod 22 the tubular lower end of the piston rod 22 and 25 the hole 25 into the upper section of the cylinder 19. Since the latter cylinder is materially smaller than the main cylinder, the air is forced on through to the rubber tube 13 and thence to the tire being inflated. 30 When the handle is raised, the ball valve 23 closes and the air above the piston in the cylinder 19 is also forced through the tube 13 to the tire.

In both the double acting pump shown in 35 Fig. 2, and the double pump shown in Fig. 3, the annular recesses 2 are made in the cast heads of the cylinders, instead of by

expanding the cylinders as set forth in Fig. 1. To admit air to the double acting cylinder 12 shown in Fig. 2, a ball-controlled intake 27 is provided at each end of the cylinder. At the upper end of the cylinder 12 of the pump shown in Fig. 2, and of the cylinder 19 shown in Fig. 3, the piston rod requires air-tight packing. This 40 is provided by giving the boss 30 a conical recess, and its screw cap 31 a corresponding conical recess. By inserting a rubber double-cone 32 in each recess of said bosses, and suitably screwing down thereabout the 45 screw cap 31, the rubber packing cones 32 are compressed about the piston rods and all escape of air about the same is prevented.

What I claim is:

A pump comprising a cylinder, a piston 55 therein having a cupped flexible washer, and a conical member located in the end of the cylinder to be engaged by the flexible washer, the space within the cylinder about the conical member being larger in diameter 60 than the interior of the cylinder, and the base of the conical member being larger in diameter than the interior of the cupped washer, whereby the washer is expanded larger than the cylinder at the end of the 65 piston's stroke and thereby made to tightly fit the same.

In testimony that I claim the foregoing invention, I have hereunto set my hand this 23rd day of October, 1914.

LOUIS A. ANDREWS.
